UNITED STATES PATENT OFFICE

PRESTON W. MARSHBURN, OF NEW YORK, AND MARSHALL T. BREKKE, OF SCARSDALE, NEW YORK, ASIGNORS TO NORTHAM WARREN CORPORATION, OF NEW YORK, N. Y., A CORPORATION OF NEW YORK

DESIGN FOR A BOTTLE

Application filed December 18, 1931. Serial No. 42,136. Term of patent 14 years.

To all whom it may concern:

Be it known that we, PRESTON W. MARSHBURN and MARSHALL T. BREKKE, citizens of the United States, residing at New York, New York, and at Scarsdale, New York, respectively, have invented a new, original, and ornamental Design for a Bottle, of which the following is a specification, reference being had to the accompanying drawing, forming part thereof.

We claim:

The ornamental design for a bottle substantially as shown.

PRESTON W. MARSHBURN.
MARSHALL T. BREKKE.
